GRINDING MACHINE

Maxwell I. Mathewson, Providence, R. I., assignor
to Brown and Sharpe Manufacturing Company,
a corporation of Rhode Island

Application April 9, 1948, Serial No. 19,939

8 Claims. (Cl. 51—166)

1

The present invention relates to improvements in grinding machines. The invention is concerned more specifically with a novel and improved arrangement of a vertically adjustable support of the cylindrical post and sleeve type for the grinding head of a grinding machine.

It is a principal object of the invention to provide a novel and improved gibbing device for maintaining a close sliding engagement of the relatively shiftable sleeve and post elements of the grinding head support which has embodied therein adjustable means for controlling the angular relation of the post and sleeve elements for effecting a fine adjustment of the angular position of the grinding wheel about the vertical post axis and transversely with relation to the rotative axis of the work.

As hereinafter more fully set forth, gibbing elements are provided on the sleeve element for engagement with follower surfaces on the post extending longitudinally thereof and disposed to take the thrust of the gibbing elements at opposite sides of the post axis, the relation of the gibs and follower surfaces referred to being such as to maintain a close sliding fit also between the engaged cylindrical bearing surfaces of the post and sleeve. In accordance with the invention, means of adjustment are provided for adjusting the relative positions of the gibs on the sleeve, and thereby the relative angular positions of the cooperating post and sleeve elements of the support. In the illustrated form of the invention shown, an extremely fine adjustment of the relative position of the gibs is effected by means of adjusting screws which are arranged to engage against and to control the position of the gibs on the sleeve element.

Two separate forms of the invention are here shown and described. In one form, the invention is embodied in a grinding machine of the general type having a stationary sleeve support and a vertically adjustable cylindrical post on which the grinding wheel support is carried. For controlling the angular position of the grinding wheel about the vertical axis of the supporting post and with relation to the rotational axis of the work, the post is grooved to provide a pair of plane surfaces extending longitudinally of the post at opposite sides of the post axis and lying substantially in a single plane. The relatively stationary sleeve support has mounted therein a pair of gibs which are arranged for engagement with the plane guiding surface referred to, and adjusting screws which are arranged to engage against the gibs and to provide means for adjusting the gibs rela-

2

tively to one another on the sleeve support. The post is supported on one side against the gibs and at its other side against the bearing surface provided by the sleeve.

5 In an alternative form the invention is illustrated as embodied in a grinding machine of the general type which is provided with a cylindrical supporting post fixed against vertical adjustment in relation to the base of the machine, and having 10 mounted thereon a vertically adjustable sleeve support for the grinding wheel head. In this embodiment of the invention, the illustrated machine is provided with a grinding wheel head vertical adjusting screw which is arranged to extend 15 downwardly along the axis of the post and is supported against axial movement with relation to the post by means of a bearing at its upper end. A cooperating lifting nut takes the form of a yoke, the arms of which extend through 20 slots in the post, and are at their outer ends secured to the cooperating vertically adjustable sleeve supporting element for the grinding wheel. In this form of the invention, the arms of the lifting nut or yoke are employed as gibs which 25 are adapted for forward and back adjustment over a small range with relation to the sleeve member to which they are attached. Adjustment is effected by means of a pair of adjusting screws screw-threaded into the sleeve member 30 for engagement against opposite ends of the yoke arms of the lifting nut. The screws are adjusted to cause the arms of the yoke, acting as gibs, to bear against one side of the slot in the vertical post through which the yoke arms project. Thrust of the gibbing devices in the opposite 35 direction is taken by the internal bearing surface of the sleeve and the external bearing surfaces of the stationary post engaging therewith. Adjustment of the adjusting screws serves to control within very close limits the angular adjusted position of the sleeve support with relation to the yoke and associated post.

40 With the above noted and other objects in view as may hereinafter appear, the several features of the invention consist also in the devices, combinations and arrangements of parts hereinafter described and claimed, which together with the advantages to be obtained thereby will be readily understood by one skilled in the art from the following description taken in connection with the accompanying drawings, in which Fig. 1 is a view 45 in left side elevation illustrating one embodiment of the invention in a grinding machine, portions of the machine having been broken away and 50 certain underlying parts being shown in section,

55

only so much of the machine being shown as is believed necessary to indicate the connection of the invention therewith; Fig. 2 is a sectional plan view taken on the line 2—2 of Fig. 1, illustrating particularly the gibbing arrangement between the vertically adjustable post and fixed sleeve elements of the grinding head support; Fig. 3 is a sectional plan view taken on the line 3—3 of Fig. 1; Fig. 4 is a somewhat fragmentary view in right side elevation illustrating an alternative embodiment of the invention in a grinding machine, only so much of the machine having been shown as is believed necessary to illustrate the connection of the invention therewith; Fig. 5 is an enlarged sectional view in front elevation taken on the line 5—5 of Fig. 4, and illustrating particularly the fixed post and vertically adjustable sleeve elements of the grinding head support; and Fig. 6 is a sectional plan view taken on the line 6—6 of Fig. 5.

Referring specifically to Figs. 1, 2 and 3 of the drawings, the invention is disclosed as embodied in a grinding machine comprising generally a base member 10, a work supporting assembly including a table 12 adapted for translatory movement, and providing support for the usual headstock and tailstock assembly indicated at 14. The grinding wheel supporting assembly of the machine consists of a grinding head 16 rigidly secured to the upper end of a vertically disposed and vertically adjustable hollow cylindrical post or column 18. The grinding head provides support for a horizontally disposed grinding wheel spindle 20 and grinding wheel 22. Power to drive the grinding wheel is provided from a drive shaft on the base through a system of belts and pulleys including a belt 24 extending upwardly within the column and adapted to ride on a pulley 26 mounted on the spindle 20.

The grinding wheel head supporting column 18 is supported for vertical adjustment within a sleeve support 30 carried in the base, such adjustment being effected by means of a vertically disposed adjusting screw 32 supported at its upper end in a bearing in the grinding head, and adjacent its lower end screw-threaded into a cooperating nut element 33 which is in turn supported in an extension 34 formed integrally with and extending rearwardly from the sleeve support 30.

In accordance with the invention, a novel gibbing arrangement is provided for the relatively movable cylindrical post and sleeve elements of the grinding wheel supporting assembly, and including provision for a forward and back adjustment of the gibbing elements through a limited range in a plane normal to the post axis to enable the grinding wheel to be accurately positioned angularly with relation to the work. As shown in Figs. 2 and 3, the post 18 is formed with two vertically extending grooves providing a pair of bearing surfaces 40, 42 which are disposed in a single plane at opposite sides of the post axis. The internal surface of the sleeve support 30 is correspondingly notched at 44, 46 to provide rectangular apertures within which are received a pair of gibs 48, 50 adapted for engagement respectively against the bearing surfaces 40 and 42. Each gib is supported against axial movement with respect to the sleeve support 30, and is adapted to be moved adjustably against its bearing surface on the post 18 by means of a pair of locating pins 51 fixedly mounted in holes in the sleeve element 30 with the inner ends thereof fitted loosely into recesses 52 in the respective

gibs 48, 50. Each gib is arranged to be acted upon by an adjusting screw 53 screw-threaded into the sleeve support 30 and arranged at its inner end to bear against a central surface portion of the gib. As shown in the figures, two locating pins 51 and one adjusting screw 53 are provided for the support of each gib. Locking screws 56 screw-threaded into the sleeve support are adapted for locking engagement against the sides of the respective adjusting screws 53. As best shown in Figs. 2 and 3 of the drawings, the internal bearing surface of the sleeve support 30 is recessed longitudinally to form a shallow depression or groove 60 in the bearing surface of the sleeve. With this construction and arrangement of the parts, the cylindrical post or column 18 is supported at one side by means of the two gibs 48, 50 bearing against surfaces 40, 42, and at its other side by the bearing surface portions of the sleeve support 30 located at each side of the cutaway area 60. An extremely close angular adjustment in the position of the supporting post and grinding head with relation to the base and work supporting elements of the machine is readily effected by adjustment of the adjusting screws 53 to move the gibs 48, 50 forward or back with respect to one another.

As best shown in Figs. 1 and 3 of the drawings, an additional gib is provided for further supporting the post 18 with relation to the sleeve 30 at a point adjacent the lower end of the sleeve. The gibbing arrangement referred to, consists of a gib 63 carried in a vertically arranged recess 64 in the sleeve member 30 for engagement with a portion of the external periphery of the post 18 at the same side with and between the two plane bearing surfaces 40, 42 above described. The gib 63 is held in position by means of two locating pins 61 mounted in holes in the sleeve member 40 and adapted to project loosely into recesses 65 formed adjacent the upper and lower ends of the gib 63. An adjusting screw 66 screw-threaded through the casing 30 is provided which engages against a centrally located surface portion of the gib. The adjusting screw 66 is locked in its adjusted position by means of a small transversely extending locking screw 69.

The grinding machine illustrated in Figs. 4, 5 and 6, as embodying the several features of the invention in an alternative form, comprises generally a base member 70 on which is mounted a work supporting assembly including a table 72 adapted for translatory movement and providing support for a headstock and tailstock assembly 74 of ordinary description. The machine is also provided with a grinding wheel assembly comprising a grinding head 76 on which is mounted a grinding wheel 78, a grinding wheel spindle 80 and an electric driving motor 82 for the spindle. In the machine illustrated in Figs. 4, 5 and 6, the grinding head 76 is formed integrally with a supporting sleeve 84 adapted for vertical adjustment on a relatively fixed hollow post or column 86. Vertical adjustment of the spindle head is obtained by means of a vertical adjustment screw 88 which extends downwardly within the column or post along its axis, and is rotatably supported at its upper end in a bearing 90 in the upper end of the stationary post 86. Toward its lower end the adjusting screw is in threaded engagement with a lifting nut 92 which takes the form of a yoke with laterally extending arms 94, 96 which project outwardly through vertical slots 98, 100 in the post 86. At their outer ends the yoke arms 94, 96 are adjustably screwed to the

supporting sleeve 84 by means of machine screws 102 which extend downwardly through oversize holes 104 in the yoke arms into threaded screw-receiving holes in the sleeve support.

In the form of the invention illustrated in Figs. 4, 5 and 6, the yoke arms 94, 96 are adapted and arranged to function as gibbing elements which engage against plane bearing surfaces at opposite sides of the post axis, and which are further arranged for forward and back adjustment relatively to the supporting sleeve in a plane normal to the post axis to provide for a limited relative angular adjustment of these parts for adjusting the position of the grinding wheel angularly with respect to the base and table elements of the machine. For adjustment of the position of the yoke arms 94, 96 with relation to the supporting sleeve 84, laterally extending adjusting screws 106, 108 are threaded into the supporting sleeve 84 to bear laterally against the yoke arms 94, 96 respectively. The adjusting screws are held rigidly in adjusted position by means of locking screws 110. With this construction and arrangement of the elements of the grinding wheel support, it will be evident that the yoke arms 94, 96 are brought to bear against the opposing walls 112, 114 respectively of slots 98, 100, and that the thrust in the opposite direction is taken up by the engagement of the cylindrical post with the internal bearing surfaces of the supporting sleeve 84. As indicated in Fig. 6, a shallow depression or groove 116 is formed in the internal surface of the supporting sleeve 84 so that the post is engaged against only the separated portions of the internal surface remaining at each side of the groove 116. As best shown in Fig. 4, an additional gibbing device including an adjusting and clamping screw 118 is provided adjacent the lower end of the supporting sleeve 84 for engagement with the peripheral surface of the post to further support the sleeve with relation to the post 86. The screw 118 when it is brought into proper adjustment allows for a good sliding fit, while in a tightened position it serves the added function of clamping the wheel slide.

It will be understood that the invention is not limited to the specific embodiments shown, and that various deviations may be made therefrom without departing from the spirit and scope of the appended claims.

What is claimed is:

1. In a grinding machine having a base, a work support and a grinding head, a vertically adjustable supporting assembly for the grinding head, which comprises cooperating vertically disposed cylindrical post and sleeve elements relatively shiftable for vertically adjusting the position of the grinding head, one of said post and sleeve elements being formed with guide surfaces disposed at opposite sides of and extending longitudinally of the cylindrical axis, and a gibbing device comprising gibbing elements supported from the other of said post and sleeve elements for engagement against said guide surfaces, and adjusting screws on said supporting element for adjusting said gibbing elements transversely of the supporting element against said guide surfaces.

2. In a grinding machine having a base, a work support and a grinding head, a vertically adjustable supporting assembly for the grinding head comprising cooperating vertically disposed cylindrical post and sleeve elements relatively shiftable for vertically adjusting the position of the grinding head, one of said post and sleeve

elements being formed with follower surfaces disposed at opposite sides of and extending longitudinally of the post axis, a gibbing device which comprises a pair of gibbing elements supported from the other of said post and sleeve elements arranged to act transversely of the post axis and at each side thereof against said follower surfaces, and adjusting means acting on said gibbing elements for adjusting the positions of said gibbing elements individually against the cooperating follower surfaces.

3. In a grinding machine having a base, a work support and a grinding head, a vertically adjustable supporting assembly for the grinding head comprising cooperating vertically disposed cylindrical post and sleeve elements relatively shiftable for vertically adjusting the position of the grinding head, one of said post and sleeve elements being formed with follower surfaces disposed in a single plane at opposite sides of and extending longitudinally of the post axis, and a gibbing device which comprises a pair of gibbing elements adjustably supported from the other of said post and sleeve elements to act transversely of and tangentially with respect to the post axis at each side thereof against said follower surfaces, and adjusting screws for adjusting the position of said gibbing elements individually transversely of the supporting element against the cooperating follower surfaces.

4. In a grinding machine having a base, a work support and a grinding head, a vertically adjustable supporting assembly for the grinding head comprising cooperating vertically disposed cylindrical post and sleeve elements relatively shiftable for vertically adjusting the position of the grinding head, said post element being formed with follower surfaces disposed at opposite sides of and extending longitudinally of the post axis, a gibbing device which comprises a pair of gibbing elements adjustably supported from the sleeve to act transversely of the post axis and to each side thereof against the follower surfaces, and adjusting means for adjusting the position of said gibs from the sleeve against said surfaces.

5. In a grinding machine having a base, a work support and a grinding head, a vertically adjustable supporting assembly for the grinding head comprising a vertically adjustable grinding head 50 cylindrical post having formed in the periphery thereof recessed follower surfaces extending longitudinally of the post axis at opposite sides thereof, a relatively fixed cooperating sleeve having formed therein cooperating gib receiving recesses, an adjusting screw and nut for effecting the vertical adjustment of the post with relation to the sleeve, and a gibbing device comprising a pair of gib blocks carried in said sleeve recesses for engagement with said cooperating follower surfaces, and adjusting means for the gibs comprising adjusting screws for adjustably positioning the gibs individually from the sleeve against said cooperating surfaces.

6. In a grinding machine having a base, a work support, and a grinding head, a vertically adjustable supporting assembly for the grinding head, comprising vertically disposed cylindrical post and sleeve elements relatively shiftable for vertically adjusting the position of the grinding head, said post element being formed with a gib engaging surface lying in a plane parallel to the post axis to provide portions of said surface disposed to receive a gibbing thrust directed tangentially to opposite sides of the post axis, a gibbing device comprising a gibbing member having

portions thereof arranged for engagement respectively against said portions of the gib engaging surface, means for supporting said gibbing member from the sleeve arranged to permit a transverse adjustment of the gibbing member relative to the sleeve, and adjusting screws operable to effect transverse and rotational adjustment of the gibbing member relative to the sleeve.

7. In a grinding machine having a base, a work support and a grinding head, a vertically adjustable supporting assembly for the grinding head comprising a vertically disposed cylindrical post element having a longitudinally extending slot passing through the walls of the post, and a sleeve element, said post and sleeve elements being relatively shiftable for vertically adjusting the position of the grinding head, means for effecting said relative longitudinal adjustment including an adjusting screw extending axially within the post and supported for rotational movement and against axial movement with relation to the post, and a yoke threaded to receive the screw and having the arms thereof passing through said slots and secured at their outer ends to the sleeve, said yoke arms acting as gibs in cooperation with follower surfaces extending longitudinally of the post provided by one side of said slot, and ad-

justing means for positioning said yoke arms transversely to the sleeve against the respective follower surfaces provided by one side of the slot in the post.

- 5 8. In a grinding machine having a base, a work support and a grinding head, a vertically adjustable supporting assembly for the grinding head comprising a vertically disposed hollow cylindrical post having a longitudinally extending slot passing through the walls of the post, and a vertically adjustable grinding head supporting sleeve carried by the post, an adjusting screw extending axially within the post and supported for rotational movement and against axial movement 10 with relation to the post, a cooperating nut comprising a yoke threaded to the screw and having the arms thereof extending through the slot, said yoke arms acting as gibs in cooperating with follower surfaces provided by one side of said slot in the post, means for securing the yoke arms to the sleeve arranged to permit a transverse adjustment of the yoke relative to the sleeve, and adjusting screws for shifting said yoke arms transversely of the sleeve against the respective follower surfaces provided by one side of the slot 15 in the post.
